DESIGN FOR A WINDSHIELD WIPER

Erwin C. Horton, Hamburg, N. Y.

Application April 5, 1934, Serial No. 51,316

Term of patent 14 years

To all whom it may concern:

Be it known that I, Erwin C. Horton, a citizen of the United States, residing at Hamburg, in the county of Erie and State of New York, have invented a new, original, and ornamental Design for Windshield Wipers, of which the following is a specification, reference being had to the accompanying drawing, forming part thereof.

The figure is a perspective view of a windshield wiper, showing my new design.

I claim:

The ornamental design for a windshield wiper, as shown.

ERWIN C. HORTON.
